(57) CLAIM

The ornamental design for a swimming pool skimmer, as shown and described.

DESCRIPTION

FIG. 1 is a top perspective view of a swimming pool skimmer showing my design;

FIG. 2 is a front elevational view thereof, the rear elevational view being a mirror image thereof;

FIG. 3 is a side elevational view thereof, as seen from the right side of the skimmer as shown in FIG. 2, the left side elevational view being a mirror image thereof;

FIG. 4 is a top plan view thereof; and,

FIG. 5 is a bottom view thereof.

1 Claim, 5 Drawing Sheets

FIG. 4
